HYDRAULIC CONTROL FOR DRILL FEEDING UNITS

Claude E. Broders, Detroit, Mich., assignor to
 Govro-Nelson Company, Detroit, Mich., a corporation of Michigan

Application January 11, 1950, Serial No. 137,992

11 Claims. (Cl. 77—33.2)

1

The present invention relates to a drill feeding unit and more particularly to hydraulic controls for regulating the rate of feed of a drill unit. The broad principle of operation of the present drill feeding unit is covered in my prior United States Patents No. 2,053,514 and No. 2,426,386 and Reissue Patent No. 21,341. In the units shown in these patents, the tool feeding spindle is advanced toward the workpiece at a feeding pressure and rate determined by the forces developed in centrifugally actuated weight members mounted in a conical feeding cup. An air dash pot arrangement is shown in my Patent No. 2,426,386 for cushioning the spindle feeding mechanism during the drilling operation.

In certain instances an hydraulic dash pot arrangement is desired in place of the air dash pot device previously used. However, it is impossible to secure a positive body of hydraulic fluid until the entrapped air has been removed therefrom so as to provide a positive hydraulic fluid cushion for the spindle feeding mechanism. Also, another problem concerns the accurate regulation of the rate of feed of the spindle and the improvement of the rapid traverse feed controls.

Accordingly, it is an object of the present invention to provide an hydraulic dash pot arrangement for use in a drill feeding unit and in which air and the hydraulic fluid are separated in the dash pot unit so that the air may be bled from the dash pot unit before the hydraulic cushioning action is required.

It is another object of the present invention to provide control means independent of the spindle feed mechanism for regulating the rate of displacement of hydraulic fluid from the hydraulic dash pot arrangement and thereby to regulate more accurately the rate of feed of the spindle.

It is still another object of the present invention to provide valve means in the hydraulic dash pot arrangement of a drill feeding unit whereby the rate of feed of the spindle in said drill feeding unit can be more accurately regulated.

It is another object of the present invention to provide in a centrifugally operated drill feeding unit a high and low speed electric motor and controls therefor operable to permit feeding of the cutting tool when the electric motor is operating at high speed and operable to permit the cutting tool to be returned to its normal starting position when the motor is at low speed, and further to provide continuous rotation of the spindle on its return to its normal starting position to aid in removal of metal chips formed by the drilling operation.

5 It is still another object of the present invention to provide an improved rapid traverse and feed control whereby the extent of rapid traverse desired of the spindle can be selectively determined and the remainder of the feed of the spindle can be controlled at a regulated rate.

Other objects of this invention will appear in the following description and appended claims, reference being had to the accompanying drawings forming a part of this specification wherein like reference characters designate corresponding parts in the several views.

In the drawings:

15 Fig. 1 is a fragmentary longitudinal section of a drill feeding unit embodying the present invention.

Figs. 2, 3 and 4 are fragmentary sectional views taken on the lines 2—2, 3—3, and 4—4 respectively, of Fig. 1.

20 Fig. 5 is a view, partly in section, taken on the line 5—5 of Fig. 1.

Figs. 6 and 7 are fragmentary sectional views taken on the lines 6—6 and 7—7, respectively, of Fig. 5.

25 Fig. 8 is a fragmentary longitudinal sectional view showing the electric motor for operating the present drill feeding unit.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, a drill feeding unit is shown having a housing 10 into which extends a drive shaft 12 journaled in bearings for rotating a spindle feeding mechanism 14. Electric switch controls 16, which are actuated by the spindle feeding mechanism 14, are provided to regulate the operation of an electric motor 17 which rotates the drive shaft 12. The spindle feeding mechanism 14 is drivingly connected to a spindle 18 on the end of which is secured a collet 20. Formed partially by the housing 10 and operably associated with the spindle feeding mechanism 14 is an hydraulic dash pot arrangement 22.

As is seen in Figure 8 of the drawings, the electric motor 17 comprises a stator 119 and a rotor 121 which is mounted on drive shaft 12 for rotation therewith. Rigidly secured to the end of drive shaft 12 is a fan 123 enclosed within the

2

fan-shell 125. A wire outlet box 127 is provided into which extend wires (not shown) for supplying power to the electric motor 17. The latter is a two speed motor for providing high and low speed rotation of said drive shaft 12, the purpose of which will be more fully explained hereafter.

Secured to one end of the stator 119 is a housing member 129 through which the drive shaft 12 extends to the spindle feed mechanism 14. A sealing means 131 is provided on drive shaft 12 to prevent passage of hydraulic fluid from within the housing 10 to the motor 17. Mounted on the housing member 129 are limit switches 133 and 135 which are actuated by the switch controls 16 and 137, respectively, in response to predetermined axial movements of the spindle feeding mechanism 14.

The electric switch control 16, when actuated by the spindle feeding mechanism 14, operates to limit the stroke of the spindle 18 by regulating the speed of the motor 17. The feed of the spindle 18 is stopped when the spindle feeding mechanism 14 engages a cam 24 on the long rod 26. This engaging action causes the long rod 26 to pivot the bell crank 28 which in turn moves the pin 30 in a longitudinal direction to actuate the limit switch 133.

When actuated by pin 30, the limit switch 133 operates to reduce the speed of the electric motor 17 to its low speed. The spindle feeding mechanism 14, which feeds the spindle 18 by the application of centrifugal forces, is so constructed and arranged that it will not feed the spindle 18 when driven by the electric motor 17 at the low speed of the latter. Instead, the spindle feeding mechanism 14 will be caused to return to its normal starting position by the action of a coil spring, later to be described.

A manually or automatically operated starting switch (not shown) is provided for increasing the speed of motor 17 from its low to its high speed. If desired, this starting switch (not shown) may be operated, for example, in response to movement of a turret which holds a workpiece so that when the turret has been properly located with respect to the drill feeding unit the starting switch (not shown) will cause the speed of motor 17 to be increased to its high speed and thereby to start the next drilling operation.

The other limit switch 135 is actuated by a control mechanism similar to that for limit switch 133. This mechanism includes the cam 32, short rod 34, bell crank 36 and pin 38. Limit switch 135 is provided to regulate the operation of auxiliary equipment used in conjunction with the present drill feeding unit. For example, limit switch 135 may be adapted to control the operation of a turret which holds the workpiece whereby on return of the spindle feeding mechanism 14 to its normal starting position the turret will be actuated to move the workpiece to a new position in preparation for the next drilling operation of the drill feeding unit.

Attention is next directed to the spindle feeding mechanism 14 as illustrated in Figure 1 of the drawings. The spindle feeding mechanism 14, as here shown, is old in the art and a more detailed description thereof can be found in my prior Patents Nos. 2,054,514 and Reissue 21,341. The present spindle feeding mechanism includes a quill 40 mounted for rotation on ball bearings 42, and secured to drive shaft 12 for rotation therewith. The spindle 18 slidably fits into the

quill 40 and a key 44 having flat surfaces 45 locks spindle 18 to quill 40 for rotation therewith. A longitudinal keyway 46 is provided in quill 40 permitting axial movement of spindle 18 with respect to said quill 40. Air and hydraulic fluid bleeder holes 47 are provided in the quill 40 for a purpose which will be explained later. A conical cup 48 is keyed to spindle 18 through the longitudinal keyway 46. The conical cup 48 is rotatable with the quill 40 while it is movable longitudinally thereof to effect longitudinal movement of the said spindle 18 relative to said quill 40. A second conical cup 50 is secured to the quill 40 which is in turn connected to the drive shaft 12. The conical cups 48 and 50 are mounted with their bases facing each other to provide an enclosed chamber of double proportions into which is loosely mounted a plurality of symmetrically disposed centrifugal weights 52. As will be readily apparent, when the drive shaft 12 is caused to be rotated at high speeds by the electric motor 17 the centrifugal weights 52 will be moved radially outwardly due to centrifugal forces and the conical cup 48, which is keyed to spindle 18 will be moved in a longitudinal direction to feed the spindle 18 to the workpiece (not shown).

In the present invention, the advancement of the spindle 18 is controlled hydraulically by a dash pot arrangement 22 including a stationary cylinder 54 formed in the housing 10 and an annular piston 56 mounted on the conical cup 48 to reciprocate and rotate within the stationary cylinder 54 and to close one end thereof. A key 58 secured in conical cup 48 extends into a longitudinal keyway 60 in the annular piston 56 whereby the piston 56 will rotate with the conical cup 48.

The other end of cylinder 54 is closed by the rotating cylinder head 64 which is located within the cylinder 54 and spaced inwardly of the end seal assembly 62 and is secured to quill 40 for rotation therewith. The end seal assembly 62 prevents leakage of the hydraulic fluid from the unit and causes it to return through the return conduit 63 to the sump 68.

Seated at its opposite ends in the cylinder head 64 and the annular piston 56 is a coil spring 66, previously referred to in explaining the operation of the control switches, which biases the annular piston against the conical cup 48 and operates to return the conical cup 48 and the various parts secured thereto for axial movement therewith to their normal starting positions at the completion of each operative cycle of the feeding unit. The coil spring 66 is designed to exert an axial force against the annular piston 56 greater than that of weights 52 when the motor 17 is operated at its low speed and less than that of weights 52 when the motor is operated at its high speed. Thus, it can be seen that when the motor 17 is operating at a relatively high speed the spindle feeding mechanism 14 will overcome the spring forces in coil spring 66 and will cause the spindle 18 to be fed to the workpiece, while when the motor 17 is operating at a relatively low speed the coil spring 66 will act to move the spindle feeding mechanism 14 back to its normal starting position. It is seen that this construction permits the cutting tool to continue rotating, but at a reduced rate of speed, when being removed from the workpiece. It is apparent that continuous rotation permits faster operation of the unit while at the same time providing a means of clearing the chips resulting from the cutting operation.

An hydraulic fluid or oil, for use with the dash pot arrangement 22, is supplied from the sump 68 which is formed within housing 10. The oil is supplied to the cylinder by way of conduit 70, valve means 72 and conduit 74.

The valve means 72 comprises two valves, the check valve 76 and the by-pass valve 78. The check valve 76 includes a valve member 80 for closing valve port 84 and a valve spring 86 for biasing the valve member 80 to a closed position. The check valve 76 operates to prevent discharge of hydraulic fluid from cylinder 54 via conduits 70 and 74 while permitting flow from the sump 68 to the cylinder 54 through these same conduits 70 and 74.

The by-pass valve 78, shown in Figs. 5 and 6 of the drawing, includes a valve stem 88 threadedly secured to valve housing 89 at 90 for axial movement in response to rotation of the valve stem 88 and locked in position by the lock nut 92. The valve stem 88 has a transverse slot 93 at its end adapted to receive a screwdriver to be rotated thereby. At its lower end, valve stem 88 is provided with a longitudinal extension or cylindrical member 94 for closing the valve port 96. The lower end of the longitudinal extension or cylindrical member 94 has a transverse slot 98 for varying the effective opening of valve port 96. It is apparent that rotation of the valve stem 88 causes axial movement of the longitudinal extension or cylindrical member 94 to vary thereby the effective opening of the transverse slot 98 at valve port 96. Thus, the rate of discharge of the hydraulic fluid from the cylinder 54 can be controlled by selectively rotating the valve stem 88, since the by-pass valve 78 is in a direct path of communication between the cylinder 54 and the sump 68.

This by-pass valve 78 is found to be decidedly superior in operation to the prior types of such valves. A more sensitive adjustment of the rate of flow of hydraulic fluid can be made and the transverse slot 98 does not readily become clogged. In the prior types of by-pass valves, where the valve was cracked slightly from the valve seat for permitting only a limited flow of hydraulic fluid, a sensitive adjustment could not be made and the very thin annular passage through which the fluid flowed, tended to clog very readily causing irregular operation of the drill feeding unit.

Reference is now made to Figs. 1-4 of the drawings for an explanation of the rapid traverse means of the present invention.

In order to provide a rapid traverse for the spindle 18, a series of axially arranged bleeder ports 100 are provided in the cylinder 54 and a valve member 102 is provided for selectively closing said bleeder ports 100. The valve member 102 has an axial conduit 104 in communication, via conduit 106 and ball check valve 107, with the interior of the said housing 10. The valve member 102 has a plurality of ports 101, axially and radially spaced, enabling any of the bleeder ports 100 to be selectively opened by rotation of knurled knob 108. Also, if it is desired, all of the bleeder ports 100 may be closed by valve member 102.

The ball check valve 107 in the conduit 106 is arranged to permit the flow of fluids from the cylinder 54 and to prevent the return of fluids thereto. This construction permits hydraulic fluid to be rapidly discharged from cylinder 54 during the rapid traverse portion of the feed of the spindle 18 while preventing air from being

drawn through conduit 106 on the return of the spindle 18 to its normal starting position.

In operation of the present feeding unit, the drive shaft 12 and the quill 40 are caused to be rotated by a two speed electric motor 17. As previously described, when motor 17 is operated at high speed the centrifugal weights 52 cause axial movement of the conical cup 43 which then causes a corresponding axial movement of the spindle 18 and the piston member 56. Rotational movement is also imparted to spindle 18 and annular piston 56 by the spindle feeding mechanism 14 through the keys 44 and 58 respectively.

When the feeding unit is in its normal starting position shown in Fig. 1, the cylinder 54 will be substantially filled with hydraulic fluid from the previous operating cycle as will be more fully described hereafter.

As the annular piston 56 advances from its normal starting position into the cylinder 54, the hydraulic fluid therein is discharged through the bleeder port 100, which has been selectively opened, until the cylinder 19 has advanced sufficiently far to close the said open port 100. Until port 100 has been closed a rapid traverse of the spindle has been provided. Thereafter, the rate of feed of spindle 18 is limited by the rate of displacement from cylinder 54 of the hydraulic fluid therein.

Thus, after the rapid traverse portion of the feeding of the spindle 18 has been completed the rate of displacement of the hydraulic fluid from the cylinder 54 is controlled by the rate at which the hydraulic fluid passes through the by-pass valve 78. It is apparent that when the effective area of the valve port 96 is selectively increased or decreased, the rate of feed of spindle 18 is correspondingly increased or decreased in direct proportion to the greater or lesser rate of displacement of the hydraulic fluid from the said cylinder 54.

When the feeding operation of the spindle has been completed by contact of conical cup 43 with cam 24, the speed of the motor 17 is reduced causing the spindle 18 to return to its normal position as explained previously, by the spring action of spring 66. The rate of return of the spindle 18 will be governed by the rate at which the hydraulic fluid is returned to the cylinder 54 via the valve means 72, by suction action of piston 56. The check valve 76 which is part of valve means 72 will be opened completely by the suction action of piston 56 and thereby will permit a relatively unrestricted flow of hydraulic fluid into cylinder 54. Thus, the cylinder will be filled with hydraulic fluid on the return of the spindle 18 to its normal starting position and the return of the spindle will be relatively rapid.

The coil spring 66 performs two separate and distinct functions in the operation of the feeding unit. As previously described, it serves to bias the spindle feeding mechanism 14 to its normal starting position shown in Fig. 1. The coil spring 66 together with annular piston 56 and cylinder head 64 also functions to separate any air that may be entrained in the oil in the cylinder 54 during the feeding operation of the spindle. It has been found that the most satisfactory cushioning effect of the oil is not achieved when any air is entrapped in the hydraulic fluid in the cylinder 54. When the feeding operation of the spindle begins, hydraulic fluid in the cylinder 54 will be bled out through the selectively opened port 100, and after the annular piston 56 has closed the selectively opened valve port

100, the cylinder 54 will be substantially filled with hydraulic fluid. The oil which now substantially fills the cylinder 54 is being rotated by the coil spring 66, the annular piston 56 and the cylinder head 64, and due to centrifugal forces the hydraulic fluid will be thrown outwardly about the walls of the cylinder and any air which may be entrapped in the hydraulic fluid will accumulate about the spindle 18.

Thus, the spinning action of the coil spring 63 and the revolving piston 56 and cylinder head 64 will act to separate the entrapped air from the hydraulic fluid, and since the air is lighter than the hydraulic fluid the air will collect about the quill 40 and spindle 18, and the slip fit between said quill 40 and said spindle 18 will permit bleeding of the air therethrough and out through holes 47. This bleeding action will remove the air in cylinder 54 and provide a solid cushion of hydraulic fluid during the entire feeding stroke, thus permitting accurate control of the feeding operation and preventing a jump of the cutting tool at the break through point.

The present construction also provides means for varying the extent of the rapid traverse of the spindle 18 during the feeding operation. Rapid traverse of the spindle 18 will occur during the feeding operation until the annular piston 56 has closed the valve port 100 which has been selectively opened. After the piston has closed said valve port 100, the feed of the spindle 18 will be determined by the rate of displacement of the hydraulic fluid from the cylinder 54 as previously described. It is apparent therefore, that the operator can determine the extent of rapid feed merely by selecting the proper setting of the valve member 102.

Having thus described my invention, I claim:

1. In a feeding unit for feeding a rotating tool to a workpiece including a housing, a rotatable and reciprocable spindle carried by said housing and adapted for feeding said tool to said workpiece, and a spindle feeding mechanism operable to rotate and reciprocate said spindle: a rapid traverse and feed control comprising a cylindrical oil chamber having an open end, piston means having a normal position within said open end for closing said open end and responsive to feeding of said spindle to further enter said oil chamber, spring means in said oil chamber for biasing said piston means toward said normal position and in opposition to feeding of said spindle, hydraulic conduit means for establishing limited communication between the oil chamber and a source of oil exterior of said oil chamber when the spindle is being fed to the workpiece and a relatively greater communication between the oil chamber and said source of oil when said spindle is being withdrawn from said workpiece, and a port in said cylindrical oil chamber in communication with the atmosphere and adapted to be closed by said piston means during the feeding of said spindle, whereby said spindle may be rapidly fed to the said workpiece when said port is open, and when said port is closed the rate of feed of said spindle is dependent on the rate of oil displacement from said oil chamber.

2. In a feeding unit for feeding a rotating tool to a workpiece including a housing, a rotatable and reciprocable spindle carried by said housing and adapted for feeding said tool to said workpiece, and a spindle feeding mechanism operable to rotate and reciprocate said spindle: a rapid traverse and feed control comprising a cylindrical oil chamber having an open end, piston means

having a normal position closing said open end and responsive to feeding of said spindle to further enter said oil chamber, spring means for biasing said piston means toward said normal position and in opposition to feeding of said spindle, hydraulic conduit means for establishing controlled limited communication between said oil chamber and a source of oil exterior of said oil chamber when the spindle is being fed to the workpiece and a relatively greater communication between the oil chamber and said source of oil when said spindle is being withdrawn from said workpiece, whereby feeding of the spindle to the workpiece is controlled by the rate of displacement of oil from said oil chamber.

3. In a feeding unit for feeding a rotating tool to a workpiece including a housing, a rotatable and reciprocable spindle carried by said housing and adapted for feeding said tool to said workpiece, and a spindle feeding mechanism operable to rotate and reciprocate said spindle: a rapid traverse and feed control comprising a cylindrical oil chamber having an open end, piston means having a normal position within said open end for closing said open end and responsive to feeding of said spindle feeding mechanism to further enter said oil chamber, hydraulic conduit means for establishing limited communication between the oil chamber and a source of oil remote from said oil chamber when the spindle is being fed to the workpiece, axially arranged ports in said cylindrical oil chamber in communication with the atmosphere, and valve means for selectively opening one of said ports, whereby the spindle may be rapidly fed to the workpiece when one of said axially arranged ports is open and when said axially arranged ports are closed the rate of feed of said spindle is dependent on the rate of oil displacement from said oil chamber.

4. In a feeding unit for feeding a rotating tool to a workpiece including a housing, a rotatable and reciprocable spindle carried by said housing and adapted for feeding said tool to said workpiece, a spindle feeding mechanism operable to rotate and reciprocate said spindle, and an hydraulic dash pot operably associated with said spindle feeding mechanism for regulating the rate of feed of said spindle in accordance with its rate of discharge of hydraulic fluid: valve controls for regulating the rate of flow of said hydraulic fluid comprising a check valve operable to prevent fluid flow from said dash pot while permitting fluid flow thereto, and a by-pass valve for permitting said hydraulic fluid to by-pass said check valve.

5. In a feeding unit for feeding a rotating tool to a workpiece including a housing, a rotatable and reciprocable spindle carried by said housing and adapted for feeding said tool to said workpiece, a spindle feeding mechanism operable to rotate and reciprocate said spindle, and an hydraulic dash pot operably associated with said spindle feeding mechanism for regulating the rate of feed of said spindle in accordance with its rate of discharge of hydraulic fluid: valve controls for regulating the rate of flow of said hydraulic fluid comprising a check valve operable to prevent fluid flow from said dash pot while permitting fluid flow thereto, and a by-pass valve for permitting said hydraulic fluid to by-pass said check valve, said by-pass valve including a cylindrical port, and a cylindrical member axially movable to close said port, said cylindrical member having a transverse slot therein whereby axial

movements of said cylindrical member will vary the effective area of opening of said cylindrical port.

6. In a feeding unit for feeding a rotating tool to a workpiece and including hydraulic control means for regulating the rate of feed of said rotating tool, a by-pass valve for regulating the rate of flow of fluid through said hydraulic control means comprising a valve housing having a first and a second port communicating with the interior thereof, a valve stem in axial alignment with one of said ports, and a longitudinal extension of said valve stem having a longitudinal transverse slot therethrough and slidable into said one of said ports for varying the effective area thereof, whereby the rate of flow of said fluid through said valve ports can be regulated by axial movement of said valve stem.

7. In a feeding unit for feeding a rotating tool to a workpiece including a housing, a rotatable and reciprocable spindle carried by said housing and adapted for feeding said tool to said workpiece, and a spindle feeding mechanism operable to rotate and reciprocate said spindle: a rapid traverse and feed control comprising a cylindrical oil chamber having an open end, piston means having a normal position within said open end for closing said open end and responsive to feeding of said spindle to further enter said oil chamber, a coil spring in said oil chamber for biasing said piston means toward said normal position and in opposition to feeding of said spindle, hydraulic conduit means for establishing limited communication between said oil chamber and a source of oil when said spindle is being fed to said workpiece and a relatively greater communication between said oil chamber and said source of oil when said spindle is being withdrawn from said workpiece, a port in the outer periphery of said cylindrical oil chamber in communication with the atmosphere and adapted to be closed by said piston means during the feeding of said spindle, whereby said spindle may be rapidly fed to said workpiece when said port is open and when said port is closed the rate of feed of said spindle is dependent on the rate of oil displacement from said oil chamber, and an aperture in said oil chamber along the axis thereof for bleeding air from said oil chamber during feeding of said spindle.

8. In a feeding unit for feeding a rotating tool to a workpiece including a housing, a rotatable and reciprocable spindle carried by said housing and adapted for feeding said tool to said workpiece, and a spindle feeding mechanism operable to rotate and reciprocate said spindle: a rapid traverse and feed control comprising a cylindrical oil chamber, piston means within said oil chamber and having a normal position at one end thereof, said piston means being responsive to feeding action of said spindle feeding mecha-

nism to move axially away from said normal position, hydraulic conduit means communicating with said oil chamber at the other end thereof, and an air bleeder port in said oil chamber between the ends thereof.

5 9. In a feeding unit for feeding a rotating tool to a workpiece including a housing, a rotatable and reciprocable spindle carried by said housing and adapted for feeding said tool to said workpiece, and a spindle feeding mechanism operable to rotate and reciprocate said spindle: a rapid traverse and feed control comprising a cylindrical oil chamber, piston means within said oil chamber responsive to feeding action of said spindle feeding mechanism to displace hydraulic fluid from said oil chamber whereby the rate of feed of said spindle is proportional to the rate of displacement of said hydraulic fluid, means within said oil chamber for separating air entrapped in said hydraulic fluid, and a bleeder aperture for bleeding said air from said oil chamber.

10 10. In a rapid traverse and feed control for use with a drill feeding unit, hydraulic control means comprising a dash pot, conduit means communicating with said dash pot and including a cylindrical portion of reduced diameter, and an axially movable cylindrical member slidably mounted in one end of said cylindrical portion, said cylindrical member having a longitudinal transverse slot whereby the effective opening at said one end of said cylindrical portion can be varied by axial movement of said cylindrical member.

15 11. In a feeding unit for feeding a rotating tool to a workpiece including a housing and a rotatable and reciprocable spindle carried by said housing and adapted for feeding said tool to said workpiece: a hydraulic dash pot for regulating the rate of feed of and for providing cushioning for said spindle, means operatively associated with said spindle for rotating about the axis of said dash pot the hydraulic fluid therein, and conduit means providing communication between the exterior of said dash pot and the interior of the dash pot adjacent the axis thereof, whereby when the hydraulic fluid is rotated any entrapped air in said hydraulic fluid will be separated therefrom and may be bled from said dash pot through said conduit means.
